DRAFT TRAP

Sterling E. Norcross, Bloomfield, N. J.

Application November 21, 1946, Serial No. 711,367

1 Claim. (Cl. 189—50)

1

This invention relates to means for blocking vertical shafts or passageways of buildings, such as elevator shafts, dumbwaiters, laundry shafts, hatchways, ventilating shafts, and the like, through which hot air or smoke or other products of combustion have a tendency to flow upwardly in case of a building or large ship catching fire and thus cause the fire to quickly spread throughout the building or other structure, it being one object of the invention to provide blocking means for the shaft or passage consisting of doors or barrier plates which are normally in a raised position close to sides of the shaft and so mounted that when released they may move downwardly to a closed position across the shaft where they will serve very effectively to shut off draft through the shaft and confine the fire to the area below the closed doors.

Another object of the invention is to provide a barrier consisting of doors or closure plates which are releasably held in a raised position against side walls of the shaft by latches, that while the doors may be automatically released when the latches are subjected to excessive heat, the latches may be manually moved to a releasing position by a person who notices the flame or excessive heat coming upwardly through a shaft and thereby permit the doors to be closed sooner than would be the case if automatic releasing of the doors was the sole means depended upon for effecting closing of the doors.

Another object of the invention is to provide closures or barriers for a shaft or passage which are pivotally mounted close to opposite side walls of a shaft for movement from a raised position to a lowered or closed position across the shaft, means being provided for checking downward swinging movement of the doors or closure plates and thus prevent danger of the doors being broken loose at their hinged sides by violently striking each other as they move to the closed position.

Another object of the invention is to provide closures for a shaft or passage which is of simple construction and very efficient in operation.

With the foregoing and other objects in view, the invention consists of a special construction and arrangement of parts illustrated in the accompanying drawing wherein:

Figure 1 is a view showing a shaft in cross section and looking down upon the improved closures for the shaft, the closures being shown in the normally opened position by full lines and indicated in a closed position by dotted lines.

Figure 2 is a view taken along the line 2—2

2

of Figure 1 and showing the shaft in vertical section and the closures in side elevation.

Figure 3 is a sectional view upon an enlarged scale taken along the line 3—3 of Figure 1.

Figure 4 is an enlarged view of a latch for holding a door in its raised or opened position.

Figure 5 is a sectional view taken vertically through the latch along the line 5—5 of Figure 4.

The shaft or passage indicated by the numeral 10 1 may be an elevator shaft or similar shaft or vertically extending passage in a building, ship or the like. When a fire starts in the basement or one of the lower floors of a building flame, smoke and other hot products of combustion are 15 carried upwardly through an elevator shaft, or like passage, and this causes the fire to quickly spread throughout the building, whereas if the shaft or passage is blocked to prevent an updraft through it, the fire could be confined to the 20 basement or lower floor where it started.

In order to permit the shaft or passage to be blocked, I have provided doors or barrier plates 2 which are of such dimensions that when they are in a lowered or horizontally extending closed 25 position they extend across each other from opposite sides of the shaft and block the shaft in such manner that flow of air, flame, and other hot products of combustion will be very effectively prevented. The doors or closure plates are 30 pivotally mounted for vertical swinging movement by hinges 3 which are mounted against opposite side walls of the shaft and when the doors are in the raised or open position, they are disposed vertically in close parallel relation to the walls 35 where they will be out of the way and not prevent an elevator from freely moving vertically in the shaft. When the doors are released, their weight will cause them to move away from the shaft walls and downwardly to a horizontal position with their free end edges in such close proximity to each other that the two doors constitute a barrier which blocks the shaft and prevent an updraft through the shaft.

The two doors are releasably held in a normally raised or open position by latches 4 which are formed of metal and each of which has a wide and flat shank 5 formed of hard metal and at the lower end of its shank a bill 6 which is formed of soft fusible metal which is strong 45 enough to hold a door in its raised position by overlapping engagement with the upper free end of the door but capable of being melted by flame or hot products of combustion moving upwardly through the shaft. When the bill is melted to 50 such an extent that it can no longer hold the

door in the raised position, the weight of the door will cause it to swing downwardly to a closed position, and since the two doors will simultaneously be released and move to the closed position, they will block the shaft and prevent further updraft through the shaft.

The latches or keepers have their shanks secured against mounting plates 7 by screws 8 which pass through vertically extending slots 9 formed in the shanks of the latches and have threaded engagement with the mounting plates, the screws also passing through plates 10 which are provided so that the latches will be spaced from the plates 7 and thus caused to slide easily in a vertical direction. Eyes 11 are mounted at upper ends of the latches and through these eyes are secured lower ends of cables or wires 12 which extend upwardly in the shaft 1 and are in such positions that they may be grasped and upward pull exerted to manually move the latches to a releasing position in case some one should discover a fire and wish to release the doors for closing movement before the doors are automatically released by melting of the bills of the latches. It will thus be seen that the doors may be automatically released or manually released and move into position to block the shaft.

If the doors were allowed to have uncontrolled downward swinging movement to a closed position and suddenly brought to a stop by engagement with each other or by their hinged ends contacting the walls of the shaft, the hinges might be broken and the doors drop downwardly through the shaft or move to such a position that the shaft would not be properly blocked. In order to prevent this, each door has attached to its free end a cable 13 which is attached at its upper or outer end to a screw eye 14 carried by the door. The cables extend through openings 15 formed through upper ends of the mounting plates and are trained about pulleys 16 carried by brackets 17 fixed to the inner faces of the mounting plates. From the pulleys the cables 13 extend downwardly through openings in the brackets, and at their lower ends carry blocks 18 which to some extent counter balance the weight of the doors but allow them to swing quickly to a closed position.

The blocks or counterweights move vertically in pockets 19 formed vertically in the side walls of the shaft and closed by the mounting plates 7, and when the doors swing downwardly towards a closed position and the cables 13 are drawn upwardly and outwardly, the blocks will be drawn upwardly until they make contact with helical springs 20 mounted under the brackets and through which the cables pass. Engagement of the blocks with the lower ends of the springs will compress the springs and check upward movement of the blocks, and downward movement of the door will be slowed sufficiently to prevent the doors from being broken by crashing movement to a closed position. After a fire

has been extinguished, the doors will be returned to a raised or open position and new latches applied to hold the doors open or the latches pulled upwardly out of the way until the doors are opened and then allowed to return to a securing position if movement of the latches to a releasing position was manually effected and their bills not melted off during the fire.

It will be seen from the foregoing description that I have provided a comparatively simple, inexpensive and efficient means for carrying out the various objects of the invention, and while I have described the elements best adapted to perform the functions set forth, it is apparent that various changes in form, proportion and in the minor details of construction may be resorted to, without departing from the spirit or sacrificing any of the principles of the invention.

Having thus described the invention, what is claimed is:

In combination with a vertical shaft having opposed side walls formed with vertically extending pockets, plates mounted against said side walls and covering said pockets, doors hinged to said walls for vertical movement from a raised position close to the walls to a closed position in which they extend towards each other in closing relation to the shaft with their free ends meeting midway the width of the shaft, latches carried by said plates and movable into and out of position to engage said doors and releasably hold the doors in the raised position, brackets extending from said plates into said pockets, pulleys carried by said brackets and disposed over the brackets opposite openings in the plates, helical springs carried by and extending downwardly from said brackets and disposed vertically in the pockets, cables attached to said doors and passing through the openings in the plates and about said pulleys and downwardly through the brackets and the springs towards lower ends of the pockets, and weights carried by lower ends of said cables and constituting counterbalance weights for said doors and serving to engage lower ends of the springs and compress the springs and thereby check closing movement of the doors when pull is exerted upon the cables by the doors during closing movement of the doors.
